HENRY J. CARY-CURR, OF ELMHURST, ILLINOIS, ASSIGNOR TO E. H. SARGENT & CO., OF CHICAGO, ILLINOIS, A CORPORATION OF ILLINOIS.

ELECTRICAL DRYING-OVEN.

1,083,592.

Specification of Letters Patent.

Patented Jan. 6, 1914.

Application filed July 25, 1913. Serial No. 781,095.

To all whom it may concern:

Be it known that I, HENRY J. CARY-CURR, a subject of the King of Great Britain, residing at Elmhurst, in the county of DuPage and State of Illinois, have invented a new and useful Improvement in Electrical Drying-Ovens, of which the following is a specification.

My invention relates to an improvement in electrical ovens of the class used, more particularly, in laboratories, for drying chemicals and other substances.

As its generally described construction, an oven of the kind referred to involves a box-like ventilated metal-bound shell provided with a hinged door and having its walls formed of suitable heat-insulating material, the box containing shield-forming slabs of heat-resisting material supported over similar slabs, which are wound helically with resistance-wire to adapt the oven to be heated by including the wires in an electric circuit containing a condenser, usually supported underneath the box, and the purpose of which is, as usual, to prevent excessive sparking at the switch in breaking the circuit. For automatically regulating the temperature in the oven, a thermostat is provided to operate a switch to open the circuit when the heat exceeds a predetermined degree, and permit closure of the same when the heat falls below that degree; and shelves are supported in the box for holding receptacles containing the matter to be dried.

The object of my invention is to improve various features in an oven of the construction described, to the primary end of increasing its efficiency.

In the accompanying drawings, Figure 1 shows my improved drying-oven by a broken view in vertical sectional elevation, the section being taken on the line 1—1, Fig. 2; Fig. 2 is a section of the same on line 2, Fig. 1; Fig. 3 is a section on the irregular line 3—3, Fig. 1; Fig. 4 shows one of the wire-bound slabs by a plan view; Fig. 5 is an enlarged section on line 5, Fig. 1, and Fig. 6 is a broken enlarged view regarded in the direction of the arrow on line 6, Fig. 1, and showing a valve-device in the bottom of the box for regulating ventilation thereof.

The box 7 shown is of rectangular shape and is supported on legs 8. The top, bottom and side walls of the box, as also its hinged door 9, are formed preferably of the insulating material known in the art by the name "transite"; and these parts should be metal-bound, as shown, for purposes both of strength and ornamentation. In the top or roof of the box are provided pipe-equipped openings 10, 10 for ventilating it, and through either of which a thermometer (not shown) may be introduced into the box, when desired, for indicating the temperature therein. Vent-openings, two of which are shown at 11 in Fig. 6, are also provided in the box-bottom and are equipped with rotary-disk valves 12 having handles 13 by which to turn them within limits defined by stops 14 and 15 at the ends of their throw, for uncovering the openings 11, more or less, to regulate ventilation through the box.

A base 16, shown as a rectangular block, and which is made of material highly resistant to heat, preferably a composition of asbestos and cement, is supported at its four corners on the box-bottom, in spaced relation thereto, by screw-legs 17 and nuts 18 embracing the bottom. At intervals along the forward and rear edges of the base rise threaded posts 19. Slabs 20 seat at holes in their ends over opposite posts upon metal spacing-sleeves 21 on the latter, the holes being lined with metal thimbles 22 to contact with the upper ends of the sleeves. Similar sleeves 23 about the posts contact at their lower ends with the thimbles, and slabs 24, slightly wider than the slabs 20, having similar holes in their opposite ends, are passed over the pairs of the posts to rest on the upper ends of the sleeves 23; and each pair of the upper and lower slabs is clamped rigidly in place by nuts 25 screwed upon the upper ends of the respective posts. Each slab 20 has an electrical resistance-wire 26 wound helically about it, as represented in Fig. 4, with its ends fastened to the opposite thimbles 22 in electrical contact therewith.

Binding-posts 27 and 28 are provided on the base 16, near one lateral edge thereof, for connecting the wires of the wound slabs

with a source of electric-current, as at a screw-plug 29 having insulating wires 30 leading from it to the binding-posts.

Three of the four posts 19 along the outer edge of the base 16 are electrically connected by a metal strip 31 on the bottom of the base, and similar conducting strips 31' and 32', shown jointed together, connect the strip 31 with the binding-post 27. The remaining post 19 of this series of four is not included in the connecting strip 31, but is connected with the strips 31', 31², at their junction, by a conducting strip 19'. The three corresponding posts 19 along the rear or inner edge of the base 16 are likewise connected by a conducting strip 32, and binding-posts 33, 34, provided on the base near its opposite lateral edge, have insulated-wire connections 30' with a condenser 35 hung rigidly on the bottom of the box for the usual purpose, hereinbefore referred to, of preventing excessive sparking at the switch in breaking the circuit. The remaining, or fourth post 19 of the last-named series of these posts is not included in the strip 32, but is connected by a conducting strip 19² with a conducting strip 36 shown jointed and connecting the binding posts 33 and 28. Of the last-named series of connected posts 19, that at the right-hand end is connected by a conducting-strip 37 with the binding post 34, which has extending from it a conducting strip 38, shown jointed and having a flat terminal strip 40 curving upwardly and rearwardly from it and projecting backwardly beyond the inner edge of the base. A similar flat terminal-strip 41 is connected by a conducting-strip 42 with the binding-post 28. By excluding the two opposite end-posts 19 from connection respectively with the strips 31 and 32, but which are electrically connected by the coil on their connecting slab 24, their connections 19' and 19² cause them to be included in the circuit when the switch is opened to cut out the coils on the other slabs 24. As the present oven is designed, each "unit", comprising a pair of the strip-connected posts 19, the members of which are connected by a coil-wound slab 24, uses about 1 $\frac{1}{10}$ amperes of current, at 110 volts, so that the three units use about 3 $\frac{1}{10}$ amperes, which is the maximum that will stand breaking at the switch without causing excessive sparking. The oven is designed to give a minimum temperature of about 60° C., depending upon the room-temperature. Whenever, though, the entire number of coils 26 employed is found to be overheating the oven, the coil connecting the two posts 19 that are not electrically connected by the respective strips 31 and 32 is taken out of circuit by removing the slab carrying it, thereby to reduce the temperature. This is the pur-

pose of having the fourth "unit" out of the control of the switch; though the same result might be accomplished by providing a switch especially for cutting out that unit, but the described arrangement saves providing the additional switch.

Transversely across the bottom of the box, underneath the same to be outside of the influence of the heat within it, extends a rectangular metal bar 43 having a post 44 extending from near its rear end upwardly through the box-bottom, and a post 45 rising therethrough from near its forward end. The post 45, which contains a threaded hole extending through it, near its upper end in the direction transversely of the box, is split vertically, in that end, to the hole, as shown at 46 in Fig. 2. A cylindrical tubular thermostat-bar 47, having a pointed inner end, holes 48 at intervals for the purpose of air-circulation through it to render uniform the influence thereon of the temperature within the box, and a hand-wheel 49 on its outer end, is journaled in the front wall of the box to work at its threaded section 49' in the aforesaid hole in the front post 45. A shaft 47', journaled in a side of the box to extend at right-angles to the thermostat-bar, is threaded at its inner end to work in an alining threaded hole through the split end of the post 45 for releasably locking the bar 47 in any position to which it may be adjusted for the purpose hereinafter explained.

On the upper end of the rear post 44 is rigidly supported, to extend transversely thereof, a metal bar 50. A relatively-heavy metal contact-strip 51 extends at a right-angle to the conducting-strip 42, parallel with and fastened to the face of the bar 50, from which it is shown to be insulated at 52; and it projects at its free tapered end beyond the inner edge of its insulating backing. Another relatively-heavy contact-strip 53 is secured at one end to the curved strip 40 to extend in front of and parallel with the face of the bar 50, to which it is fastened at 54. This contact-strip is divided, and its sections are connected by a flat spring 55 of relatively-thin metal. The free, tapered end of the strip 53 overlaps the corresponding end of the contact-member 51 of this switch-device; and the pointed extremity of the thermostat-bar abuts against the face of the contact-member 53, near that end.

Shelves 56, preferably of reticulated wire metal-bound about the edges, as indicated in Fig. 1, are supported, to be withdrawably insertible into the oven through its doorway, on ledges 57 provided in the box on its opposite side-walls in tiers above the slabs 24.

To operate the oven for drying material

in receptacles introduced into it on the shelves, and with the door closed and the proper connection made of the plug 29 with a source of electric current, the latter heats 5 the resistance-wires 26 to the required degree of incandescence for producing the desired temperature in the oven. The attainment of this temperature may be ascertained by means of a thermometer in- 10 serted through an opening 10. When this temperature has been attained, the thermostat-bar, which is then unlocked, is turned to advance its inner end against the contact-member 53 and separate the 15 latter slightly from its companion-member 51, whereupon the shaft 47 is turned to clamp the split end of the post 45 about the thermostat-bar and lock it in its adjusted position. With the oven-door closed, the ad- 20 justment of the bar 47 may be performed under inspection of the hot interior of the oven through a mica-covered peep-hole (not shown) in the front wall of the box. With the circuit thus opened at the switch, the 25 thermostat-bar shrinks lengthwise sufficiently to permit the contact-member 53, by its resilient action, to meet the companion-member 51 and again close the circuit, which remains closed until the resultant heating of 30 the oven becomes slightly excessive and expands the thermostat-bar longitudinally to cause it to open the switch.

By providing for locking the thermostat-bar securely in the adjusted position thereof, 35 the important advantage is afforded of insuring maintenance of the predetermined heat-condition, and preventing undesirable or injurious variation therein by accidental or meddlesome turning of the bar. The di- 40 vided construction of the contact-member 53 is also of material importance, inasmuch as it enables the connected sections to be made of relatively heavy metal, and the light spring 55 connecting them affords a resilient 45 joint to flex and cause the free contacting section of that member to instantaneously and completely break contact with the mem- 50 ber 51; whereas, if the member 53 were a continuous piece of spring-metal, its sepa- 55 ration from the companion-member would drag and, by thus failing of instantaneous action, tend to keep the circuit closed until the predetermined temperature became ex- cessive, with injurious consequences to the material under treatment in the oven.

I do not claim herein the thermostatic switch-mechanism for controlling the circuit in the oven, but reserve the right to claim the same in a future application for 60 Letters Patent.

Another advantage of my improved construction lies in supporting the post-carrying bar 43 outside of the box, where it is not subject to the extending and contract-

ing influence upon it, were it inside the 65 same, of the variations in temperature therein, which would tend to disorganize the parts and render the action of the thermo- 70 stat inaccurate and unreliable. Still another advantage, worth mentioning, is due 75 to providing the slabs 24 of somewhat greater width than the wire-wound slabs below them, since thereby the lower slabs are shieldingly covered by the relatively wider slabs against spilling on the latter 80 of the contents of the receptacles, as by upsetting the same, on shelves 56 while being introduced into the box or withdrawn, which might tend to impair the resistance-wires or 85 their function.

I realize that considerable variation is possible in the details of construction thus specifically shown and described, and I do not intend by illustrating a single, specific or preferred embodiment of my improve- 90 ments to be limited thereto; my intention being in the following claims to claim protection upon all the novelty there may be in my invention as broadly as the state of 95 the art will permit.

What I claim as new and desire to secure by Letters Patent is—

1. An electrical oven of the character de- 95 scribed, comprising a box vented through its top and bottom and having bottom vent- 100 openings provided with a rotary regulating valve, a slab in the box wound with resist- 105 ance-wire, an electric circuit containing a switch, and automatically-operating means in the box for opening the switch.

2. An electrical oven of the character de- 105 scribed, comprising a box, a slab supported on metal posts in the box and wound with resist- 110 ance-wire, an electric circuit including said wire, an electric thermostat-operated switch included in said circuit within the box, and a relatively-wider slab supported on said posts in spaced relation to and cover- 115 ing the wire-wound slab.

3. An electrical oven of the character de- 110 scribed, comprising a box, a base supported in the box in spaced relation to its bottom and having opposite metal posts rising from it and surrounded by spacing-sleeves, an electric circuit, a slab having end-openings 115 containing metal thimbles at which it is supported upon the posts on said sleeves, said slab being wound with resistance-wire connected at its ends with said thimbles, and the thimbles being included in said circuit, 120 an electric switch contained in said circuit, and means for opening and closing the switch.

4. An electrical oven of the character de- 125 scribed, comprising a box, a base supported in the box in spaced relation to its bottom and having opposite metal posts rising from it and surrounded by pairs of spacing

4
sleeves, an electric circuit, a slab having end-openings containing metal thimbles at which it is supported upon the posts between said sleeves, said slab being wound with resistance-wire connected at its ends with said thimbles and the thimbles being included in said circuit, a slab having end-holes at which it surrounds said posts and rests on the upper members of the sleeve-pairs, nuts on

the upper ends of the posts for clamping together the parts thereon, an electric switch contained in said circuit, and means for opening and closing the switch.

HENRY J. CARY-CURR.

In presence of—
NELLIE B. DEARBORN,
AMY C. FISCHER.
